RECEIVER-ASSEMBLY FOR FIREARMS

David M. Williams, New Haven, Conn., assignor
to Western Cartridge Company, New Haven,
Conn., a corporation of Delaware

Application February 26, 1943, Serial No. 477,207

3 Claims. (Cl. 42—20)

The present invention relates to improvements in firearms, and relates more particularly to improvements to receiver-assemblies and associated parts therefor.

One of the objects of the present invention is to provide a superior receiver-assembly for firearms which includes a receiver and a receiver-plug mounted in the rear end of the said receiver to exclude foreign matter from the same but which is, in addition, so constructed and arranged as to enable the receiver-plug or closure to discharge other functions by its being shifted from one position to another.

Another object of the present invention is to provide a superior receiver-assembly for firearms which includes a receiver and a rotatable receiver-plug so constructed and arranged as to enable the said receiver-plug to function as means for rendering the firearm safe against unintentional discharge.

A further object of the present invention is to provide a superior receiver-assembly of the character referred to and wherein a rotatable receiver-plug or closure is employed, which latter is so constructed and so related to associated features as to act as a seal for lateral apertures in the receiver proper when the said receiver-plug is rotated into one of its functioning positions.

A still further object of the present invention is to provide a superior firearm-structure comprising a receiver, a rotatable receiver-plug and a reciprocating breech-bolt, and so constructed and arranged as to enable the said receiver-plug to function as releasable restraining-means for restraining chosen movements of the said breech-bolt.

With the above and other objects in view, as will appear to those skilled in the art from the present disclosure, this invention includes all features in the said disclosure which are novel over the prior art and which are not claimed in any separate application.

In the accompanying drawings, in which certain modes of carrying out the present invention are shown for illustrative purposes:

Fig. 1 is a broken view partly in side elevation and partly in vertical central-longitudinal section of the central portion of a firearm embodying the present invention and showing the hammer as cocked and the rotary receiver-plug in its normal position wherein the firearm may be discharged at will;

Fig. 2 is a top or plan view thereof;

Fig. 3 is a view similar to Fig. 1 though less comprehensive and showing the rotary receiver-

plug turned into its safety position to effect the positive retirement of the hammer;

Fig. 4 is a top or plan view partly in horizontal section of the structure shown in Fig. 3;

Fig. 5 is a broken detail transverse sectional view taken on the line 5—5 of Fig. 1;

Fig. 6 is a similar view taken on the line 6—6 of Fig. 3;

Fig. 7 is a broken detail transverse sectional view taken on the line 7—7 of Fig. 1;

Fig. 8 is a similar view taken on the line 8—8 of Fig. 3;

Fig. 9 is a broken transverse sectional view taken on the line 9—9 of Fig. 3;

Fig. 10 is a broken top or plan view of the receiver, the rear portion of the barrel, and associated parts, and showing the rotary receiver-plug turned into its safety position and the breech-bolt and action-slide partly retired;

Fig. 11 is an underside view of the structure shown in Fig. 10;

Fig. 12 is a broken top or plan view of the rear portion of the receiver, together with the receiver-plug and showing the latter rotated into position to permit its complete withdrawal from the receiver;

Fig. 13 is a view in rear elevation of the structure shown in Fig. 12;

Fig. 14 is a broken view of the structure partly in side elevation and partly in vertical central-longitudinal section, and showing the breech-bolt retired to the limit of its rearward movement, preparatory to being locked into substantially the said position by the partial rotation of the receiver-plug;

Fig. 15 is a view similar to Fig. 14 but in side elevation only and showing the receiver-plug turned sufficiently to effect the locking-back of the breech-bolt and hence also the locking-back of the action-slide;

Fig. 16 is a top or plan view of the structure shown in Fig. 15;

Fig. 17 is a transverse sectional view taken on the line 17—17 of Fig. 14;

Fig. 18 is a similar view taken on the line 18—18 of Fig. 15;

Fig. 19 is a broken longitudinal sectional view taken on the line 19—19 of Fig. 15 with a portion of the receiver in plan;

Fig. 20 is a perspective view of the rotary receiver-plug viewing the same mainly from the top;

Fig. 21 is also a perspective view of the receiver-plug but viewing the same mainly from the underside thereof;

Fig. 22 is a top or plan view of the receiver detached;

Fig. 23 is a view in rear elevation of the receiver;

Fig. 24 is a top or plan view of the breech-bolt detached;

Fig. 25 is a view thereof in front elevation; and

Fig. 26 is a view in side elevation of the breech-bolt detached.

The particular firearm herein chosen for illustration in connection with a preferred form of the present invention includes a stock 30 which supports a receiver 31, a trigger-plate 32 and a barrel 33. The said barrel 33 is rigidly attached at its rear end to the receiver 31 in a manner common in firearm-structures. Throughout the major portion of its length, the barrel 33 has extending over its upper portion a barrel-cover 34 which like the stock 30 is preferably formed of wood or other heat-insulating and shock-absorbing material.

The receiver 31 above referred to is formed with a bore or mechanism-receiving chamber 35 extending longitudinally therethrough and having a contour which is substantially cylindrical in character. Reciprocating and oscillating in the mechanism-receiving chamber 35 in the receiver 31 is a breech-bolt 36 which throughout the majority of its length is of cylindrical form externally and which is formed at its forward end with a relatively-short radially-extending locking-lug 37 and a diametrically-opposite and relatively-long combined operating-and-locking lug 38. Both of the lugs 37 and 38 fit into suitable recesses in the receiver 31 when the breech-bolt is at the limit of its forward movement, to effect the locking of the breech-bolt in such position.

The breech-bolt 36 has the outer portion of its combined operating-and-locking lug 38 projecting into a cam-recess 39 formed in the inner face of the rear portion of an action-slide generally designated by the reference character 40. The coaction of the lug 38 and the surfaces of the cam-recess 39 serve to operatively interconnect the action-slide 40 and the breech-bolt 36 for effecting the movement of the latter in a manner well known in the art and corresponding generally to the operative interconnection employed in the well-known Garand military rifle. In its rear portion, the action-slide 40 is also formed with an outwardly-extending operating-handle 41 by means of which the action-slide itself and also the breech-bolt 36 connected thereto may be retired in a manner as will hereinafter appear.

At its forward end, the action-slide 40 is formed with an integral head generally designated by the reference character 42 and including a transversely-extending relatively-heavy end-wall 43. From the perimeter of the head 42 just referred to, a relatively-thin lateral-wall 44 extends forwardly and normally laterally envelops a cylinder-lug 45 when the parts are in the positions in which they are shown in Fig. 1.

The cylinder-lug 45 above referred to is formed integral with and offsets downwardly from the barrel 33 adjacent the rear end of the latter. The said cylinder-lug is formed with a rearwardly-opening piston-chamber 46 having its longitudinal axis extending in substantial parallelism with the longitudinal axis of the barrel 33. Leading forwardly and upwardly from the closed front end of the piston-chamber 46 is an inclined gas-passage 47 communicating at its

forward upper end with the bore 48 of the barrel 33 so as to conduct gas under pressure from the said bore to the forward portion of the piston-chamber 46 for purposes as will hereinafter appear.

Reciprocating in the piston-chamber 46 of the cylinder-lug 45 is a piston generally designated by the reference character 49. The said piston includes a relatively-large-diaetered head 50 having a substantially-gastight reciprocating fit in the forward portion of the piston-chamber 46, and a rearwardly-projecting stem 51. The said stem 51 of the piston 49 projects rearwardly through a bushing 52 which is threaded into the rear portion of the rearwardly-opening piston-chamber 46 in the cylinder-lug 45. The rearward movement of the piston 49 is limited by the engagement of the conically-contoured rear face of its head 50 with the similarly-contoured forward edge of the bushing 52. The stem 51 of the piston 49 normally has its rear end impinging against the forward face of the relatively-heavy end-wall 43 of the head 42 of the action-slide 40, as is shown in Fig. 1.

The action-slide 40 above referred to is suitably guided for movement lengthwise of the firearm-structure in any suitable manner not requiring detailed description herein. The said action-slide, however, is yieldingly urged forwardly into the position in which it is shown in Figs. 1 and 2, by a helical breech-closing spring 53 acting at its forward end through the intermediary of a breech-closing plunger 54. The rear portion of the breech-closing plunger fits within the forward end of the breech-closing spring 53 while its forward end is engaged with the end-wall 43 of the action-slide head 42. The breech-closing spring 53 extends rearwardly into a longitudinal spring-pocket 55 formed in the right side-wall of the receiver 31.

By thrusting forwardly upon the head 42 of the action-slide 40 the breech-closing spring 53 exerts a constant but yielding effort to maintain the said action-slide in its foremost position and hence also acts through the intermediary of the said action-slide to maintain the breech-bolt 36 in its breech-closing position.

The stock 30 before referred to includes a butt-stock-portion 56 and an integral forestock-portion 57. At about the junction-point of its butt-stock-portion 56 and forestock-portion 57, the stock 30 is formed with a vertical-longitudinal passage 58 extending therethrough from top to bottom and designed and adapted for the reception of portions of the firearm-structure, including the trigger-plate 32 before referred to and as is especially well shown in Fig. 1. Leading forwardly from the vertical-longitudinal passage 58 just referred to is a relatively-deep upwardly-opening longitudinal groove 59 located mainly in the upper portion of the forestock-portion 57.

Leading rearwardly from the upper rear-portion of the vertical-longitudinal passage 58 in the stock 30 is a longitudinal groove 60 which is relatively shallow as compared to the groove 59 before referred to. Leading downwardly from the groove 60 just referred to is an upwardly-opening shallow recess 61 which communicates at its forward end with the rear end of the vertical-longitudinal passage 58, as is especially well shown in Figs. 1 and 3. The lower portion of the rear-wall of the passage 58 is formed with a notch 62 in which is installed a head-plate 63.

Extending vertically between the shallow recess 61 and the notch 62 and in the portion of the

stock 30 lying immediately to the rear of the passage 53 therein, is a vertical cylindrical passage 64. Installed partly in the upwardly-opening recess 61 and partly in the vertical cylindrical passage 64 is a tensioning-fixture 65 having a cylindrically-contoured upper face substantially corresponding in transverse curvature to the transverse curvature of the underside of the receiver 31.

Inserted upwardly through the head-plate 63 and threaded into the lower end of the tensioning-fixture 65 is the relatively-large-dia-metered body-portion 66 of a tensioning-screw or member 67. Formed integral with and upwardly-extending from the body-portion of the tensioning-screw 67 is a relatively-flexible tensioning-pin 68 normally projecting upwardly through a coupling-passage 69 formed in the lower rear-portion of the receiver 31.

The trigger-plate 32 before referred to is coupled in any approved manner to the under-portion of the receiver 31 and coacts with the assembly comprising the head-plate 63, tensioning-fixture 65 and associated parts in a manner not requiring detailed description herein but shown and described in detail in copending application Serial No. 473,111 filed January 21, 1943.

Mounted in the trigger-plate 32 and normally extending upwardly into the mechanism-receiving chamber 35 of the receiver 31 is a hammer generally designated by the reference character 70 and turning upon a hammer-pin 71 extending transversely of the said trigger-plate 32. The said hammer 70 is formed on its forward upper face with an impact-lug 72 which is adapted to strike the rear-face of the laterally-projecting head 73 of a firing-pin 74 to effect the discharge of the firearm. The said firing-pin 74 is carried by and reciprocates in the breech-bolt 36 before described, in a manner familiar to those skilled in the art. The hammer 70 is provided with a downwardly-and-rearwardly-extending integral hammer-tail 75 having on its lower forward corner a cocking-abutment 76 which is adapted to be engaged by the under-face of a sear-nose 77 rearwardly extending from the upper end of a sear-arm 78 forming an integral feature of a trigger 79. The said trigger 79 is mounted for pivotal movement upon a trigger-pin 80 extending transversely across the lower rear-portion of the trigger-plate 32.

For the purpose of swinging the hammer 70 in a clockwise direction (as viewed in Fig. 1), a helical hammer-spring 81 is employed. The said hammer-spring 81, in the instance shown, encircles a plunger 82 and thrusts the same generally in an upward direction. The outer end of the plunger 82 bears in the under portion of the hammer-tail 75 near the junction thereof with the main portion of the hammer, while the opposite end of the said plunger reciprocates in a trunnion-block 83 pivoted in the trigger-plate 32. As shown, the lower or inner end of the hammer-spring 81 bears upon the upper surface of the trunnion-block 83 and by urging the plunger 82 outwardly, the said hammer-spring serves, in turn, to urge the hammer 70 to turn in a clockwise direction when released by the sear-arm 78.

The receiver 31 before referred to generally speaking is of tubular form though at its rear end the upper wall of the receiver is cut away to substantially the horizontal median line of the receiver to form a receiver-lip 84 substantially of semicircular form in cross section having the coupling-passage 69 before referred to located in the bottom portion thereof. Formed in the upper

right-hand wall-portion of the receiver 31 and leading forwardly from the rear end thereof is a guide-slot 85. At its forward end the guide-slot 85 is widened out toward the left side of the receiver to provide, in effect, an ejection-opening 86 through which cartridge-cases may be ejected when the breech-bolt 36 is retired rearwardly. In its lower wall forwardly of the receiver-lip 84, the receiver 31 is formed with a clearance-passage 70a leading downwardly from the mechanism-receiving chamber 35 in the receiver and providing for the movement of the hammer 70.

The receiver-lip 84 at the rear end of the receiver 31 is formed with a series of parallel coupling-ribs 87 extending crosswise thereof and following the cylindrical contour of the inner or upper face of the said receiver-lip 84 as is especially well shown in Figs. 22 and 23.

Fitting within the otherwise open rear-end of the mechanism-receiving chamber 35 of the receiver 31 is a receiver-plug or closure generally designated by the reference character 88. The said receiver-plug is cylindrically contoured, and generally speaking may be said to be of relatively-deep cup-shaped form and comprising an end-wall 89 and a substantially-annular lateral-wall 90 integral with and projecting forwardly from the said end-wall 89. On the periphery of its rear portion, the receiver-plug 88 is formed with a series of coupling-ribs 91 respectively spaced from each other in a direction longitudinally of the receiver-plug and extending around substantially the lower half of the periphery of the said receiver-plug. The said coupling-ribs 91 of the receiver-plug 88 normally interfit between the similarly-shaped coupling-ribs 87 formed in the upper surface of the receiver-lip 84. The lengths of both of the sets of coupling-ribs 87 and 91 in a direction circumferentially of the receiver-plug 88 are slightly less than 180° to permit the disengagement of the said sets of coupling-ribs one from the other in a manner as will hereinafter appear. Normally, however, when the coupling-ribs 91 of the receiver-plug 88 are interengaged with the coupling-ribs 87 of the receiver-lip 84, the said receiver-plug is firmly locked in place in the rear-portion of the mechanism-receiving chamber 35 of the receiver 31 against axial displacement and with capacity, however, for transverse turning movement, all for purposes as will more fully hereinafter appear.

Radially projecting from the rear portion of the outer periphery of the receiver-plug 88 is an integral lug 92. Extending radially through the end-wall 89 of the receiver-plug 88 and also radially outwardly through the said lug 92 is a socket 93. Mounted in the inner end of the said socket is a helical spring 94 which outwardly urges a plunger 95 mounted in the outer portion of the said socket 93 and normally projecting outwardly beyond the outer end thereof for purposes as will presently appear.

Fitting over the radial lug 92 at the rear end of the receiver-plug 88 is a hollow finger-piece 96 pivoted to the said lug 92 by a pivot-pin 97 located forwardly of the spring-pressed plunger 95 and extending substantially perpendicularly with respect thereto as is especially well shown in Figs. 2 and 19. The spring-pressed plunger 95 presses outwardly upon the portion of the finger-piece 96 located to the rear of the pivot-pin 97 and hence exerts a yielding effort, under the force of the spring 94, to turn the finger-piece 96 in a counterclockwise direction as viewed in Figs. 2 and 19. At its forward portion, the finger-piece

96 is formed with an integral inwardly-projecting tang 98 which, in a manner as will hereinafter appear, serves to releasably retain the receiver-plug 88 in any one of a plurality of positions of rotation within the rear end of the mechanism-receiving chamber 35 in the receiver 31. On occasion the inner end of the tang 98 just referred to is adapted to fit into a clearance-notch 99 formed in the periphery of the receiver-plug 88.

In the portion of its periphery having coupling-ribs 91 thereon, the receiver-plug 88 is formed with a circumferentially-extending limiting-slot 100 which receives the upper end of the tensioning-pin 68 before referred to. The coaction of the respective opposite ends of the limiting-slot 100 with the respective opposite sides of the upper end of the tensioning-pin 68 serves to limit the rotation of the receiver-plug 88 so long as the receiver 31 and associated parts remain assembled with the stock 30.

Adjacent one end of the transverse limiting-slot 100 just above referred to, the receiver-plug 88 is formed with a longitudinal clearance-slot 101 which is designed to provide clearance for the laterally-projecting head 73 of the firing-pin 74 in a manner as will hereinafter appear. The forward portion of the clearance-slot 101 is relatively wide in a direction circumferentially of the receiver-plug and extends to and intersects the forward end of the said receiver-plug, as is especially well shown in Fig. 21. The forward portion of the longitudinal clearance-slot 101 also serves on occasion to accommodate the radially-projecting locking-lug 37 at the forward end of the breech-bolt 36 under conditions as will hereinafter appear. About midway of its length, one wall of the longitudinal clearance-slot 101 is shaped to provide a sloping hammer-retiring cam 102 which serves to coact with the upper end of the hammer 70 to forcibly retire the same in a manner as will hereinafter appear.

At a point substantially diametrically opposite the relatively-wide forward end of the longitudinal clearance-slot 101 above referred to, the receiver-plug 88 is formed with another longitudinal clearance-slot 103 which intersects the forward end of the receiver-plug and extends but a relatively-short distance rearwardly therefrom. The last-mentioned clearance-slot 103 is adapted to receive the combined operating-and-locking lug 38 which projects radially from the forward end of the breech-bolt 36 at a point substantially diametrically opposite the locking-lug 37 thereon. Formed integral with one wall of the clearance-slot 103 and projecting circumferentially in a counterclockwise direction therefrom, is a bolt-retaining finger 104 having a rearwardly-facing bolt-retaining abutment 105 which latter is adapted to engage on occasion with the forward face of the combined operating-and-locking lug 38 of the breech-bolt 36 to restrain the same in its retired position, all in a manner as will hereinafter appear.

As will be apparent from the foregoing, the receiver-plug 88 is adapted to be turned about its longitudinal axis within the rear-end of the mechanism-receiving chamber 35 in the receiver 31, to various degrees for various purposes as will hereinafter appear. The said receiver-plug may be turned manually by means of its pivotal finger-piece 96.

Before proceeding to describe the operation of the firearm-mechanism shown and described, it is thought best to first outline some of the functions of the receiver-plug 88.

Among the functions discharged by the receiver-plug 88 may be mentioned the following:

(a) Serves as a closure for the rear-end of the receiver 31 to exclude foreign matter therefrom;

(b) Serves as a closure for the rear-portion of the guide-slot 85 in the receiver 31 when the receiver-plug is turned into its so-called "safety" position and when the breech-bolt is in its forward breech-closing position;

(c) The inner face of its end-wall 89 serves as a stop to check the rearward movement of the breech-bolt as the same is thrown back following the discharge of the firearm;

(d) Serves to retire and lock the hammer 70 or other firing-member against turning movement to effect the discharge of the firearm, when the receiver-plug is turned into its so-called "safety" position;

(e) Serves when in its safety position to permit but limit the rearward travel of the breech-bolt so as to allow the same to be retired to a degree sufficient for the user to ascertain the presence or absence of a cartridge in the cartridge-chamber of the firearm but without permitting the full extraction and ejection of such cartridge; and

(f) Serves to releasably hold the breech-bolt in substantially its fully-retired position.

30

OPERATION

Let it be assumed that the hammer is cocked as shown in Fig. 1, and that the receiver-plug 88 is turned into its so-called "firing" position as shown in Figs. 1, 2, 5 and 7. The term "firing" position as employed herein refers to the position of the receiver-plug 88 when the same is in a position of non-interference with the discharge of the firearm.

40

With the hammer 70 cocked as shown in Fig. 1, the firearm may be discharged by pulling rearwardly upon the finger-piece of the trigger 79 to thereby release the hammer 70 to the action of the hammer-spring 81. Upon its release, the hammer 70 will snap rapidly in a clockwise direction to impinge its impact-lug 72 against the head 73 of the firing-pin 74, thereby driving the same forwardly and effecting the discharge of the firearm in a manner well understood in the art.

50

As soon as the firearm is discharged, gas under pressure from the bore 48 of the barrel 33 will pass downwardly through the inclined gas-passage 47 into the forward end of the piston-chamber 46. The entry of gas under pressure into the

55

piston-chamber as just described will serve to force the piston 49 rearwardly to correspondingly move the action-slide 40. The rearward travel of the piston 49 will continue a short distance until the rear face of its head 50 engages with the forward edge of the bushing 52. The action-slide

60

and associated parts will, however, continue by virtue of their now-acquired momentum to move a much greater distance rearwardly, i. e., until the breech-bolt 36 has reached substantially the position in which it is shown in Fig. 14 wherein its rearward movement is checked by the forward face of the end-wall 89 of the receiver-plug 88.

65

In traveling rearwardly as above described, the action-slide 40 will act through its cam-recess 39 to first partly turn the breech-bolt 36 in a counterclockwise direction and then to move the same rearwardly into the position in which it is shown in Fig. 14. In the figure referred to it will be noted that the combined operating-and-locking lug 38 has been accommodated in the longitudi-

70

nal clearance-slot 103 while under these conditions the diametrically-opposite locking-lug 37 of the breech-bolt will be accommodated in the forward portion of the relatively-wide clearance-slot 101.

The rearward movement of the breech-bolt as just above described will, in a manner well understood in the art, effect the extraction and ejection of the case of the just-fired cartridge.

Following the full retirement of the breech-bolt as above described, the breech-closing spring 53 will assert itself and again restore the parts to the positions in which they are shown in Figs. 1 and 2 preparatory to another discharge of the firearm.

The "safety" setting of the receiver-plug 88

When the hammer is cocked and the firearm is in readiness for discharge as shown particularly well in Figs. 1 and 2, the firearm may be rendered "safe," so to speak, by first swinging the forward portion of the finger-piece 96 of the receiver-plug 88 outwardly and rearwardly and then raising the said finger-piece to thereby turn the said receiver-plug in a counterclockwise direction (as viewed from the rear of the firearm). In this manner the parts just referred to will shift from the positions in which they are shown in Figs. 1, 2, 5 and 7 into the positions in which they are shown in Figs. 3, 4, 6 and 8. The swinging of the finger-piece 96 (prior to being lifted) about its pivot-pin 97 is to retire its tang 98 outwardly from the clearance-notch 99 in the receiver-plug and from beneath the upper wall of the longitudinal guide-slot 85. Then upon being lifted as described, the tang 98 of the finger-piece 96 will come to rest in a stop-notch 106 in the upper wall of the receiver 31.

The turning movement of the receiver-plug 88 as above described will cause the hammer-retiring cam 102 thereof to act against the adjacent upper portion of the hammer 70 and thereby swing the same in a counterclockwise direction into the position in which the said hammer is especially well shown in Fig. 3, and thereafter interpose the portion of the lateral wall 90 of the receiver-plug between the said hammer and the firing-pin 74. Thus, the hammer 70 is retired into a so-called "over-cocked" position and positively retained therein by the receiver-plug so that when the latter is restored to its so-called "firing" position, the hammer will swing in a clockwise direction and again be caught by the sear-nose 77 of the sear-arm 78.

In turning the receiver-plug 88 from its firing position (Fig. 1) into its safety position (Fig. 3), should the operator attempt to swing the finger-piece 96 so that its tang 98 moves beyond the stop-notch 106 in the receiver, the engagement of one wall of the transverse limiting-slot 100 with the upper end of the tensioning-pin 68 will serve to check such movement.

In its turning movement as above described the receiver-plug 88 remains firmly coupled to the receiver 31 against axial movement relative thereto by the interlocking effects of the two sets of coupling-ribs 87 and 91.

After the firearm has been rendered safe as above described, the user of the firearm will on occasion commence to wonder as to whether or not the firearm is loaded. With ordinary firearms the user will draw back upon the breech-bolt to secure an answer to the question and in most instances will unintentionally extract and eject a cartridge if one is at the time in the car-

tridge-chamber of the firearm. It is very difficult in ordinary firearms to withdraw the breech-bolt only partly, since the start of the retirement of the breech-bolt is usually the most

5 difficult and, following its starting, the breech-bolt moves relatively easily, with the result that before the user knows what has happened the cartridge is completely extracted and ejected and in all probability lost in the dirt. With the present construction, however, and when the receiver-plug is in its safety position, the user of the firearm may readily secure an answer to the question as to whether or not a cartridge is in the cartridge-chamber by moving the breech-bolt rearwardly by means of the action-slide 40. The rearward movement of the breech-bolt will, however, be limited to a distance corresponding to but a fraction of the length of the cartridge, due to the fact that the laterally-projecting

20 head 73 of the firing-pin 74 will engage with a forwardly-facing stop-abutment 107 located on a forward edge of the receiver-plug adjacent one side of the circumferentially-widened forward-portion of the longitudinal clearance-slot 101 in the receiver-plug 88 just forwardly of the hammer-retiring cam 102 therein.

25 In this manner the user of the firearm will be able to ascertain the presence or absence of a cartridge in the cartridge-chamber of the firearm without running the hazard of unintentionally effecting the ejection of such cartridge, due to the unintentional full retirement of the breech-bolt.

30 It is also to be noted that when the receiver-plug 88 is turned into its safety position which is the normal position under which the firearm would be carried, the lateral wall 90 of the receiver-plug has swung into position whereby it acts as a closure for the rear-portion of the longitudinal guide-slot 85 in the receiver 31 to thereby effectively exclude foreign matter from the interior of the receiver. Under the conditions just described, the ejection-opening 86 and associated cuts or openings in the receiver are 35 closed by the periphery of the breech-bolt 36 itself.

The bolt-retaining position of the receiver-plug 88

50 As is well known to users of firearms, it is very often desirable to hold a breech-bolt in its fully-retired position and in the present structure and as has been before noted, the receiver-plug 88, or its equivalent, is designed to effect such result.

55 When it is desired to hold the breech-bolt 36 in substantially its rearmost position, the said breech-bolt may be retired into such position by drawing rearwardly upon the action-slide 40 to bring the parts into the positions in which they are shown in Fig. 14. This movement is accomplished while the receiver-plug 88 is in its so-called "firing" position, as shown.

60 When the breech-bolt is retired as just described, its combined operating-and-locking lug 38 will be entered into the longitudinal clearance-slot 103 in the forward part of the lateral wall 90 of the receiver-plug, so that the front face of the said lug 38 will be located rearwardly 65 of the plane of the bolt-retaining abutment 105 of the receiver-plug 88.

70 With the breech-bolt retired and positioned as just above referred to, the same may be latched or retained in such position by rotating the receiver-plug 88 in a counter-clockwise di-

rection from its so-called "firing" position into the position in which it is shown in Figs. 15, 16, 18 and 19, which position is one intermediate its firing position and safety position.

When the receiver-plug 88 is swung from its firing position into its bolt-latching position, the bolt-retaining finger 84 of the said receiver-plug will be shifted into a position in front of the combined operating-and-locking plug 38 of the breech-bolt. Now when the breech-bolt 36 is freed of manual restraint, the breech-closing spring 53 will assert itself and endeavor to return the breech-bolt and associated parts to their foremost positions. The interposition of the bolt-retaining abutment 105 of the receiver-plug in the path of return movement of the breech-bolt will, however, check such forward movement. The tang 98 of the finger-piece 96 of the receiver-plug 88 will under the conditions just described rest upon the sloping upper wall of the guide-slot 85 in the receiver 31. The parts will be restrained in the positions just referred to by the friction between the abutment 105 and the front face of the lug 38 of the breech-bolt.

A slight manual pressure exerted upon the upper face of the finger-piece 96 of the receiver-plug 88 will serve to turn the receiver-plug from its bolt-retaining position into its firing position and thereby release the previously-latched breech-bolt and associated parts for forward movement into the positions in which they are particularly well shown in Figs. 1 and 2, in readiness for the discharge of the firearm. The release of the breech-bolt from its retention may also be effected by slightly rearwardly moving the breech-bolt to thereby relieve the friction between the parts 38 and 105. This action will permit the spring 94 to act through the finger-piece 96 and the tang 98 to cause the latter, by camming action on the sloping upper wall of the guide-slot 85, to return the receiver-plug 88 to its firing position.

When the finger-piece 96 is swung downwardly, its tank 98 will swing inwardly beneath the upper wall of the guide-slot 85 in the receiver 31 and enter the clearance-notch 99 in the periphery of the receiver-plug 88. In this manner the receiver-plug is latched in its firing position to guard against the unintentional or accidental movement thereof out of such position. To effect the turning movement of the receiver-plug out of its firing position, it is first necessary to swing the finger-piece 96 thereof so as to withdraw the tang 98 from beneath the upper wall of the guide-slot 85 in the receiver 31.

The removal of the receiver-plug 88 from the receiver

In order to remove the receiver-plug 88 from the receiver, it is first necessary to dismount the unit comprising the receiver 31, trigger-plate 32, barrel 33 and associated parts from the stock 30. This removal serves to completely remove the coupling-passage 69 in the receiver-lip 84 from the upper end of the tensioning-pin 68.

Now by swinging the tang of the finger-piece 96 of the receiver-plug 88 outwardly, the entire receiver-plug may be turned substantially 180° in a counterclockwise direction from its firing position into its releasing position, as indicated in Figs. 12 and 13. The rotation of the receiver-plug 88 to the extent just referred to will serve to completely disengage its series of coupling-ribs 91 from the similar coupling-ribs 87 of the receiver-lip 84. The receiver-plug 88 may now be

withdrawn axially rearwardly completely out of the rear end of the receiver 31, as indicated by broken lines in Fig. 12. Following the removal of the receiver-plug 88, the breech-bolt 36 may be removed through the now-open rear end of the receiver after the action-slide 40 has been disengaged from the lug 38 of the breech-bolt.

General considerations

For purposes of description, the hammer 70, the firing-pin 74 and the breech-bolt 36 may be viewed as comprising portions of a firing-mechanism, since the said parts are jointly and severally involved in effecting the discharge of the firearm.

The receiver-plug 88 or its equivalent as thus constructed and arranged not only serves to positively lock the hammer against moving into its firing position but also acts as a stop for the breech-bolt when the same is thrown fully backwardly as a result of the discharge of the firearm. The said receiver-plug also acts as a stop to limit the rearward movement of the breech-bolt to a slight distance as shown in Figs. 10 and 11, to permit the ascertainment of the presence or absence of a cartridge in the cartridge-chamber of the firearm. In addition to the functions just described, the receiver-plug 88 excludes foreign matter from entry directly into the rear end of the receiver and also excludes foreign matter from radial entry into the receiver through its guide-slot 85 when the receiver-plug is turned into its safety position. Also and as before noted, the receiver-plug may be utilized to hold back the breech-bolt in its fully-retired position.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. A firearm-structure including in combination: a receiver having a longitudinal mechanism-receiving chamber therein intersecting its rear end; a transversely-oscillatable receiver-closure located at the rear of the said receiver in position to close the rear end of the mechanism-receiving chamber therein; coupling-means constructed and arranged to releasably couple the said receiver-closure to the said receiver against axial displacement but with capacity for transverse oscillating movement with respect thereto; a breech-bolt reciprocating in the mechanism-receiving chamber of the said receiver adjacent the said receiver-closure and having a rearwardly-facing stop-abutment; a forwardly-facing stop abutment carried by the said receiver-closure and movable by a transverse oscillating movement of the said receiver-closure into and out of position to engage with the stop-abutment of the said breech-bolt to block the normal rearward movement of the said breech-bolt; a pivotal hammer extending in the mechanism-receiving chamber of the said receiver adjacent the said receiver-closure; and blocking-means carried by the said receiver-closure and movable by a transverse oscillating movement of the said receiver-closure into position to coact with the said pivotal hammer to block the firing movement thereof coincidentally with the movement of the aforesaid forwardly-facing stop-abutment into position to

engage with the rearwardly-facing stop-abutment of the said breech-bolt.

2. A firearm-structure including in combination: a receiver having a longitudinal mechanism-receiving chamber therein intersecting its rear end and also having a lateral opening leading outwardly from the said mechanism-receiving chamber; a transversely-oscillatable hollow receiver-closure located at the rear of the said receiver in position to close the rear end of the mechanism-receiving chamber therein and having a lateral opening movable by a transverse oscillating movement of the receiver-closure into and out of registration with the lateral opening in the said receiver; coupling-means constructed and arranged to releasably couple the said receiver-closure to the said receiver against axial displacement but with capacity for transverse oscillating movement with respect thereto; a breech-bolt reciprocating in the mechanism-receiving chamber of the said receiver adjacent the said receiver-closure and provided with a laterally-projecting lug movable into and out of the respective lateral openings in the receiver and receiver-closure, the said breech-bolt having a rearwardly-facing stop-abutment; a forwardly-facing stop abutment carried by the said receiver-closure and movable by a transverse oscillating movement of the said receiver-closure into and out of position to engage with the stop-abutment of the said breech-bolt to block the rearward movement thereof; a pivotal hammer extending in the mechanism-receiving chamber of the said receiver adjacent the said receiver-closure; and blocking-means carried by the said receiver-closure and movable by a transverse oscillating movement of the said receiver-closure into position to coact with the said pivotal hammer to block the firing movement thereof when the said receiver-closure is oscillated into position to bring its lateral opening out of registration with the lateral opening in the said receiver.

ceiver coincidentally with the movement of the aforesaid forwardly-facing stop-abutment into position to engage with the rearwardly-facing stop-abutment of the said breech-bolt.

3. A firearm-structure including in combination: a receiver having a longitudinal mechanism-receiving chamber therein intersecting its rear end and also having a lateral opening leading outwardly from the said mechanism-receiving chamber; a transversely-oscillatable hollow receiver-plug extending within the rear of the mechanism-receiving chamber in the said receiver in position to close the same, the said receiver-plug also having a lateral opening movable by a transverse oscillating movement of the receiver-plug into and out of registration with the lateral opening in the said receiver; coupling-means constructed and arranged to releasably couple the said receiver-plug within the said receiver against axial displacement therein but with capacity for transverse oscillating movement with respect thereto; a breech-bolt reciprocating in the mechanism-receiving chamber of the said receiver adjacent the said receiver-plug and provided with a laterally-projecting lug movable into and out of the respective lateral openings in the receiver and the receiver-plug, the said breech-bolt having a forwardly-facing retaining-abutment on its said lug; a rearwardly-facing bolt-retaining abutment carried by and located in the lateral opening in the said receiver-plug and movable by a transverse oscillating movement of the said receiver-plug into and out of position to engage with the retaining-abutment of the said breech-bolt to hold the breech-bolt in its retired position when the said receiver-plug is turned into position to bring its lateral opening partly out of registration with the lateral opening in the said receiver.

DAVID M. WILLIAMS.
